United States Patent Office.

MICHEAL McGILL, AND JOSEPH E. TYNAN, OF PATERSON, NEW JERSEY

Letters Patent No. 64,684, dated May 14, 1867.

IMPROVED STREET-LAMP LIGHTER.

The Schedule referred to in these Letters Patent and making part of the same.

TO ALL WHOM IT MAY CONCERN.

Be it known that we, MICHEAL McGILL and JOSEPH E. TYNAN, of Paterson, in the county of Passaic, in the State of New Jersey, have invented certain new and useful improvements in Hand-Lanterns for Lighting Street or other Lamps in exposed situations; and we hereby declare that the following is a full, clear, and exact description of the construction and operation of the same, reference being had to the annexed drawings, making a part of this specification, in which—

Figure I is a side elevation of the lantern when closed.

Figure II is a sectional elevation when opened in the manner and for the purpose hereinafter described.

Figure III is a front view of the lantern when open.

The same letters of reference represent like parts in the several figures.

a is the usual chimney or cowl common to other lanterns. *b b* are two guard-wings, attached to the lower section of the lantern *c'*, and between which wings the flame is protected from gusts of wind whilst it is being applied to the lighting of street lamps, in the manner seen in Figs. II and III. An opening, *f'*, is situated in the front of the upper portion of the case *c*, Fig. III, through which light is emitted when the lantern is closed, the other lights *f* showing no light, except when the lantern is being used as in Fig. II. Each of those openings in the wings *b b* and in the front *c* are provided with mica, horn, or glass windows to enable, by their transparency, the operator to see when he applies the flame of the lantern to the wick of the stationary lamp. The bottom portion *c'* of the lantern is attached to the upper portion *c* by the hinge *g*, situated at the back of the lower portion of the case and in front of the handle *d'*. Immediately above the handle *d'*, and attached to the upper portion of the lantern *c*, is a thumb-piece, which, upon being pressed by the thumb whilst the hand grasps the handle *d'*, the bottom or lower part *c'*, containing the lamp *e*, is swung back into a horizontal or nearly horizontal position, as seen in Fig. II, when the flame may be readily applied to the wick of the lamp to be lighted, protection from wind meantime being afforded to the flame by the guard-wings *b b*, which, being fast upon the lower portion *c'*, assume also a horizontal position. The lamp *e* is an ordinary oil lamp, fitting snugly into the bottom portion *c'*, and which may be easily and readily removed and replenished with oil or wick when necessary. The red lines, Fig. II, illustrate the manner in which the flame of the lantern is applied to the wick of the ordinary petroleum lamp.

The object of our invention is to provide a lantern for the purpose of lighting street or other lamps which will not be affected, or its flame blown out, by sudden gusts of wind when being applied for the purpose of ignition. This we accomplish by the above arrangement and combination of parts when operated in the manner described; that is to say; the upper and lower case *c* and *c'* bound together by the hinge *g*, and operated or opened by the thumb-piece *d* and handle *d'*, the guard-wings *b b* being meanwhile thrown into such a position as to effectually protect the flame of the lamp *e* whilst being used to ignite the wick of the stationary lamp.

What we claim as new, and desire to secure by Letters Patent, is—

A hand-lantern, constructed as and for the purposes described.
